UNITED STATES PATENT OFFICE.

BURDETTE A. LEWIS, OF PLAINVILLE, CONNECTICUT.

DESIGN FOR ENDS OF BELTING.

Specification forming part of Design No. 5,978, patented July 9, 1872.

Specification describing a Design for the Ends of Machine Belting, invented by BURDETTE A. LEWIS, of Plainville, in the county of Hartford and State of Connecticut.

The nature of my design is fully represented in the accompanying drawing, to which reference is made, and consists in the peculiar form of the holes therein, as hereafter described.

B represents a portion of an ordinary machine-belt, and a represents the holes which are designed to receive an ordinary belt-lacing. The contour of the holes a is composed of three straight lines and three curved lines,

thus forming a triangular-shaped hole with rounded corners, as shown. The holes a are placed near the end of the belt, with one of the straight sides toward the said end and parallel therewith.

I do not claim any particular number of holes for the end of a belt; but

I claim as my invention the design for the ends of machine-belt, as shown.

BURDETTE A. LEWIS.
